WIRE FEEDING MECHANISM

Benjamin B. Blanchard, Swampscott, Mass., assignor to United Shoe Machinery Corporation, Paterson, N. J., a corporation of New Jersey

Application April 27, 1936, Serial No. 76,555

8 Claims. (Cl. 1—20)

This invention relates to wire feeding mechanism and is illustrated as embodied in a machine of the type shown in United States Letters Patent No. 1,839,238, granted January 5, 5 1932, on the application of F. L. MacKenzie.

The machine mentioned has for its purpose the formation, and driving into a work piece, of wire staples. In the MacKenzie machine a wire is drawn from a reel by the rotation of a pair 10 of feed wheels between which it is held and its end is thrust over an inside former, which is simply a metallic abutment having its thickness substantially equal to the distance between the insides of the legs of the staple to be formed 15 and driven. An outside former, which is of inverted U-shape, is then driven down over the wire piece, which has just previously been cut from the body of the wire by a pair of knives, and bends it into a two-legged staple. The inside former is then withdrawn, leaving the staple 20 frictionally held in the outside former, in driving position, after which a driver descends through a suitable channel in the outside former and forces the staple down through a driving throat into a work piece held between the throat and a clinching anvil movable to hold the work 25 against the throat.

The length of the legs of the staple is determined by shifting the feed wheels and the knives 30 toward or from the axis of the driver and inside former, and altering the rotary feeding movement of the feed wheels accordingly. For example, if the staple legs are desired to be $\frac{1}{8}$ " longer than those of the staples for which the 35 machine is then set, the feed wheels and knives are moved $\frac{1}{8}$ " farther from the axis of the inside former and the feeding movement of the wheels is changed to feed $\frac{1}{4}$ " more wire. The machine thus far described antedated the 40 invention of MacKenzie, the shifting of the feeding and cutting mechanism being theretofore accomplished by means of a hand lever and cam which brought about the above-described change in position of the feed wheel rotating shaft such 45 that the length of wire fed was thereby varied. Such a machine is shown in United States Letters Patent No. 1,016,930, granted February 13, 1912, on the application of W. H. Borden.

The invention of MacKenzie, described and 50 claimed in the above-mentioned patent, rendered the shifting of the feed wheels and knives automatic by operating it in connection with the upward movement of the clinching anvil through which the work was clamped between this anvil and the driving throat, so that the

changes in the lengths of the staple legs were determined by the changes in the thickness of the work, thus avoiding difficulty resulting from failure of the operator of the Borden machine to change the wire feed when he should. The 5 MacKenzie machine, however, left unchanged the feed wheel rotating device of Borden, which was subject to considerable inaccuracy in use due to looseness resulting from wear, to which the mechanism was highly sensitive. 10

It is a principal object of the present invention to correct this difficulty, and I have accordingly provided a mechanism for effecting and regulating the wire feed which avoids the defects of the Borden mechanism, which is positive and 15 accurate in operation, and which retains the advantageous characteristics of both the Borden and MacKenzie machines.

To this end I have provided a novel staple forming organization having a wire feeding 20 means operated by an arm having a fixed throw, irrespective of the length of the staple being formed, in which the operative connection between the arm and the feeding wheel consists of a single link and crank arm connection, a construction having minimum susceptibility to wear. 25

In accordance with another feature of the invention I have provided means for correcting minor inaccuracies in the said link and crank arm mechanism, when rigorous accuracy is desirable. This is done by means of a cam control 30 for regulating the length of the crank arm in accordance with the movement between the anvil and throat which, as in the MacKenzie machine above mentioned, effects the desired shifting of the feed wheel slide. 35

These and other features of the invention comprising certain combinations and arrangements of parts will be apparent from the following description of a preferred embodiment 40 of the invention shown in the drawings, in which—

Fig. 1 is a rear elevation, partly broken away; 45
Fig. 2 is a side elevational detail of the feed wheel rotating mechanism;

Fig. 3 is a diagram illustrating the effect of shifting the feeding wheel carriage, as seen from the front of the machine; and

Fig. 4 is an expanded perspective view of the mechanism shown in Fig. 3. 50

As suggested above, the illustrated machine is similar to the machine of the MacKenzie patent cited, in all respects except the wire feeding mechanism, and the MacKenzie patent should be consulted for a full description of the main 55

part of the mechanism. Fig. 1 herein is a view corresponding to Fig. 3 of the MacKenzie patent.

The main shaft 16, the carrier 54, sliding on two rods 58, with its feed wheel 44, the release lever 50 which carries a cooperating presser roll (herein numbered 52), the operating lever 80 for the feeding device, pivoted at 76, and its cam roll 82 and cam track 84 mounted on the shaft 16, the vertically movable anvil or clinching abutment 108, the screw 112 carried by it, the bell-crank lever 122 pivoted at 118, with its stud 124, cooperating with the screw 112 when the abutment 108 is raised, in order to operate the rack 138 which slides the carriage 54 on the rods 58, in accordance with the thickness of the work between the driving throat 140 and the abutment 108, all operate as described in the MacKenzie patent above mentioned, and the anvil 108 is raised by a treadle to clamp the work against the throat 140, as shown in the patent. All the elements mentioned (except 52) are numbered as in the MacKenzie patent.

The novel mechanism for operating the feed wheel 44 will now be described. The wheel 44 is integrally mounted, i. e., rigidly fastened, on a shaft 60, pivoted in the sliding carrier 54, and the shaft 60 carries an integral crank arm 130 at its rear end. The lever 80 carries a toothed segment 132 at its lower end cooperating with a toothed segment 134 keyed on one end of a shaft 136 rotatable in the machine frame 10 (Fig. 2). The shaft 60, being mounted in the sliding carrier 54, can assume a variety of positions relatively to the shaft 136. The shaft 136 has an arm 139 mounted on its end remote from the segment 134, and a simple link 141 pivotally connects the arm 139 and the arm 130, at the points 142, 144, respectively.

The lever 80, being controlled by the cam 84, has a fixed throw, irrespective of the length of the staple being formed, and so, therefore, have the segment 134 and the arm 139. The movement of the center 144, arm 130 and shaft 60, due to the pull of the link 141, as the arm 130 swings from the position 130^a shown in Figs. 1 and 3, to the position 130^b (Fig. 3), depends on the position of the carriage 70 and the shaft 60.

This is illustrated in Fig. 3, which shows the mechanism in three positions as set for staples of three different lengths. The arm 139 is shown in its two extreme positions, 139^b and 139^c, corresponding to the beginning and ending of the feeding movement. The link 141 is shown in two full line positions, 141^a and 141^b, corresponding to its positions at the beginning and ending of the feed for a short-legged staple, the center of the shaft 60 being then at 60^{ab}. For a long-legged staple, the center 60 is moved to 60^{cd}, and the initial and final positions of the link 141 are shown in full lines at 141^c and 141^d, respectively. The wire feed is proportional to the angles measured by the arcs 144^a—144^b and 144^c—144^d, whose centers are at 60^{ab} and 60^{cd}, respectively, in the two cases, and the latter is evidently much larger than the former. Fig. 3 is illustrative, merely, and is not drawn carefully to scale.

It is obvious that the amount of wire fed depends only on the initial and final positions of the arm 130, it being immaterial just how the arm 130 gets from one position to the other. It may be remarked that it is quite simple to design the machine to deliver exactly the amounts of wire requisite for staples of two lengths of leg. It will be remembered that the center 60 is to slide by

an amount exactly equal to the desired difference in length of the staple leg, and that the feed wheel 44 is then to feed twice as much more wire as this for the longer staple as for the shorter. The center 60 is laid out on the slide axis 58 (Fig. 3) at 60^{ab} and 60^{cd}, and the arcs 144^a—144^b and 144^c—144^d are laid off symmetrically relatively to the axis 58. These arcs are computed from the radius of the feed wheel 44 and the desired total lengths of wire. Arcs are then struck from these four points 144, with radii all equal to the length of the link 141, which will locate the two points 142^b and 142^c. The center 136 is the intersection of the axis 58 with the perpendicular bisector of the line 142^b—142^c. This layout will make the machine feed exactly right for the longest and shortest staples. It was found, however, that while it would deliver the proper lengths of staple wire in the cases of staples of the maximum and minimum lengths for which the machine was intended, it would deliver a little too much wire (arc 144^c—144^d, Fig. 3) for a staple of medium length, and owing to the method by which the staples are formed such error in the length of the wire would make the legs of the staple of correspondingly unequal length.

In accordance with the present invention this difficulty is corrected by a change in the described construction of the arm 130. The arm 130 is formed with a longitudinal slot 146 (Figs. 1 and 4) in its end, the pivot pin at 144 being located in and fitting this slot. The position of the pivot pin at 144 in the slot 146 is controlled by a link 143 (Figs. 1 and 3) joining the pin and the vertical arm 150 of a lever, shown as a bell crank, pivoted at 151 on an arm running down from the carriage 54, and having a horizontal arm 152 the end of which rests in a cam slot 154 formed in a stationary cam 156 mounted on a bracket 158 carried by the frame 10 of the machine. The positions 144^b and 144^c which will give an arc of the required length may be found empirically by the designer (the center 60 remaining undisturbed), and the requisite position of the bell crank 150, 152, and the requisite point 160 (Fig. 45 3), of the cam slot 154, determined in consequence. Only one point on the cam 156 will correspond to a given length of staple leg since the pivot 151 moves with the carriage 54, so that the shifting of the center 60 in accordance with the thickness of the work will determine the proper length of staple in all cases.

Having described my invention, what I claim as new and desire to secure by Letters Patent of the United States is:

1. In a staple forming and driving machine, a wire feeding mechanism comprising an arm having a fixed throw irrespective of the length of staple being formed, a wire feeding wheel having an axis shiftable relatively to the pivotal axis of the said arm to vary the effect of the throw of the said arm on the wire feeding wheel, said feeding wheel having also an integral crank arm, and a link connecting the two said arms.

2. In a staple forming and driving machine, a wire feeding mechanism comprising an arm having a fixed throw irrespective of the length of staple being formed, a wire feeding wheel operated by the said arm and having an axis shiftable relatively to the pivotal axis of the said arm to vary the effect of the throw of the said arm on the wire feeding wheel, and mechanism controlled by the thickness of the work in the machine for determining the position of the said shiftable axis.

3. In a staple forming and driving machine, a
5 wire feeding mechanism comprising an arm having
a fixed throw irrespective of the length of
staple being formed, a wire feeding wheel having
10 an arm linked to said first-mentioned arm
and having an axis shiftable relatively to the
pivotal axis of the said first-mentioned arm to
vary the effect of the throw of the said first-
15 mentioned arm on the wire feeding wheel, and
mechanism controlled by the thickness of the
work in the machine comprising a slide on which
the said shiftable axis is mounted.
4. In a staple forming and driving machine, a
driving throat and an anvil, one of which is mov-
15 able to grasp a work piece between them, a wire
feeding mechanism, means for operating the
feeding mechanism, said feeding mechanism being
shiftable relatively to the operating means
20 to vary the feeding effect of said operating means
on the feeding device, and mechanism for re-
fining said variation of the feeding effect comprising
a crank arm of variable length, a lever
25 having one arm connected to the feeding device
to vary the length of said crank arm, and a cam
controlling the other arm of said lever.
5. In a staple forming and driving machine, an
arm having a fixed throw, a wire feeding wheel
30 having an integral arm, a link connecting said
two arms, a movable member in which said feed-
ing wheel is mounted, whereby the rotative effect
of said fixed throw upon said feeding wheel can
35 be varied, a movable work grasping element, a
lever connected to said movable member and op-
erated by the movement of the said work gras-
ping element, and means, comprising a cam, op-
erated by the last-mentioned movement, for
varying the effective length of the arm on the
feeding wheel to vary the effect of the first-
mentioned arm upon the feeding wheel.
6. In a staple forming and driving machine, an
arm having a fixed throw, a wire feeding wheel
5 having an integral arm, a link connecting said
two arms, a movable member in which said feed-
ing wheel is mounted, whereby the rotative effect
of said fixed throw upon said feeding wheel can
10 be varied, a movable work grasping element, a
lever connected to said movable member and op-
erated by the movement of the said work gras-
ping element, and means operated by the last-
15 mentioned movement for altering the effective
length of the second said arm.
7. In a staple forming and driving machine, an
arm having a fixed throw, a slide, an anvil, and
a driving throat arranged to be moved relatively
20 toward each other to grasp a work piece, mecha-
nism for moving said slide controlled by said rela-
tive movement, a wire feeding wheel mounted on
said slide and having a crank arm, a link con-
necting said arm to said crank arm, the connec-
25 tion between said link and crank arm being of
pin-and-slot form, and a cam and connections
for moving the pin in the slot as said slide moves.
8. In a staple forming and driving machine, an
arm having a fixed throw, a slide, an anvil, and
a driving throat arranged to be moved relatively
30 toward each other to grasp a work piece, mecha-
nism for moving said slide controlled by said rela-
tive movement, a wire feeding wheel mounted on
said slide and having a crank arm with a slot in
35 its outer end, a link pivoted at one end to said
arm and having a pin fitting in said slot at its
other end, a lever mounted on the said slide, a
link connecting one arm of the lever to said pin
having the slot may be varied, and a cam con-
25 trolling the position of the other arm of said lever.

BENJAMIN B. BLANCHARD.
